UNITED STATES PATENT OFFICE.

ULYSSES S. RICKMAN, OF NEWTON, KANSAS, ASSIGNOR OF ONE-HALF TO LOUIS B. SWARTZ, OF NEWTON, KANSAS.

SUPPORT FOR PIPE-HANGERS.

1,072,361.

Specification of Letters Patent.

Patented Sept. 2, 1913.

Application filed February 6, 1913. Serial No. 746,540.

To all whom it may concern:

Be it known that I, ULYSSES S. RICKMAN, a citizen of the United States, residing at Newton, in the county of Harvey and State 5 of Kansas, have invented certain new and useful Improvements in Supports for Pipe-Hangers, of which the following is a specification.

This invention comprehends improvements in pipe hanger supports which are 10 to be used in connection with concrete floors, ceilings, etc.

The primary object of the invention resides in the provision of a pipe hanger support which shall be of extremely simple construction, cheap to manufacture, and which 15 may be very firmly secured within a plastic flooring or the like.

With these and other objects in view, as 20 will become more apparent as the description proceeds, the invention consists in certain novel features of construction, combination, and arrangement of parts, as will be hereinafter described and claimed.

25 For a complete understanding of my invention, reference is to be had to the following description and accompanying drawings, in which,

Figure 1 is a fragmentary vertical sectional view showing my device secured in a plastic flooring, the false flooring being also shown, Fig. 2 is a fragmentary view in elevation, showing the lower end of my support with a pipe hanger secured thereto, 30 Fig. 3 is a fragmentary top plan view, Fig. 4 is a fragmentary perspective view of the upper end of my hanger support, showing one form of anchoring bar, and, Fig. 5 is a longitudinal sectional view through the upper end of the support, the anchoring bar 35 being shown in elevation.

Referring in detail to the drawings by numerals, 6 designates a portion of a false flooring, which is used to support the plastic 40 flooring 7 until the same has hardened, after which the false flooring is removed.

My device is supported by the false flooring while the plastic flooring is being poured, and when the false flooring is removed said 45 device is left firmly embedded in the plastic flooring. The device includes a cylindrical socket 8, open at each end and internally threaded, as indicated at 9, for its entire length. An annular flange 10 is formed 50 upon the socket 8 adjacent its inner end

and is adapted to engage the inner side of the false flooring 6, the socket proper being extended through an opening in said flooring. A plurality of fasteners 11 may, if desired, be driven into the flooring 6 60 through apertures formed in the flange 10 so as to securely fix the socket. A body member 12 which, in this instance has been shown as being a tube externally threaded adjacent each end as indicated at 13, is 65 adapted to be threaded at its lower end within the socket 8. The upper end of the body member 12 has threadedly secured thereto a cylindrical cap having a body wall 14 and end wall 15. The cap is internally threaded 70 for a portion of its length adjacent its inner end to engage the threads upon the member 12. The body wall 14 of the cap is formed with a pair of diametrically opposed key-hole slots 16 and with a pair of diametri- 75 cally opposed circular openings 17. The vertical plane which extends through the center of the openings 17 extends at right angles to the vertical plane which extends through the center of the key-hole slots 16. 80 The openings 17 are essentially equal in diameter to the diameter of the upper enlarged ends of the key-hole slots 16 and are positioned somewhat closer to the end wall 15 than are the enlarged ends of said slots. 85 Anchoring rods 18 and 19 are driven through the openings 17 and the enlarged ends of the slots 16 and provide means whereby the member 12 may be threaded into the socket 8. The distance which the cap will overlap 90 the threaded tube 12 is determined by the length of the threaded portion within said cap.

When the plastic flooring 7 hardens and the false flooring 6 has been removed the 95 anchoring rods 18 will securely hold the pipe hanger support in the plastic flooring. The fasteners 11 may be nipped off so as not to project below the surface of the plastic flooring. A pipe hanger comprising a ring 20 100 and a threaded shank 21 is adapted to be threaded within the exposed end of the socket 8 to support a pipe.

When my device is used where the space is 105 so limited that only one anchoring rod could be used, I substitute for the anchoring rods a bar 22 which is rectangular in cross section and which is essentially equal in width to the length of the key-hole slots 16. The bar is run through these slots and a locking pin 23 110

forced through the opening 17 into engagement with the upper edge of the bar. This upper edge is formed with an arcuate notch 24 to receive the pin. This construction is 5 provided because a single rod does not have the required strength, whereas the bar 22 is sufficiently strong to support any weight likely to be placed on the hanger support.

It is to be understood that while I have 10 shown and described the preferred embodiment of my invention, I do not wish to be limited to this exact construction, combination, and arrangement of parts, but may make such changes as will fall within the 15 spirit and scope of the invention.

Having thus described my invention, what I claim is:—

The combination with a plastic base, of a

pipe hanger support partly embedded therein, said support comprising a cylindrical 26 socket internally threaded, a laterally projecting flange surrounding said socket adjacent its inner end, said flange being adapted to be secured to a false base, a threaded body member extending from the inner end of the 25 socket, a cap mounted upon the upper end of the body member, said cap being formed with two pairs of openings, and anchoring rods extending through said openings.

In testimony whereof I affix my signature 29 in presence of two witnesses.

ULYSSES S. RICKMAN.
